MEAT SKEWER

William L. Bonnell, Atlanta Road, Newnan, Ga.

Filed May 12, 1958, Ser. No. 50,835

Term of patent 14 years

(Cl. D81—10)

Fig. 1 is a side elevation view of a meat skewer showing my new design thereof;

Fig. 2 is an enlarged cross-sectional view taken along line 2—2 of Fig. 1; and

Fig. 3 is an enlarged cross-sectional view taken along line 3—3 of Fig. 1.

I claim:

The ornamental design for a meat skewer as shown.
